Patented Aug. 17, 1926.

UNITED STATES PATENT OFFICE.

JOSEPH AXT, OF MILWAUKEE, WISCONSIN.

SPIRIT LEVEL.

Application filed March 9, 1926. Serial No. 93,482.

This invention relates to an improved spirit level, having more particular reference to a novel mounting for the liquid containing vials.

The invention has more particular reference to a level structure wherein a pair of spirit containing vials are utilized, these being disposed in side by side relation for securing a more accurate result from the use of the instrument.

My principal aim is to provide a novel means whereby the vial can be disposed in side by side spaced parallel relation, but can be adjusted with respect to each other to insure true parallelism, and simultaneous action of the indicating bubbles.

Other features and advantages of the invention will become apparent from the following drawings and description.

In the accompanying drawings forming a part of this application, and in which like numerals are employed to designate like parts throughout the same:

Figure 1 is a top plan view of a fragment of a body portion of a level showing the improved device associated therewith.

Fig. 2 is a longitudinal section through Fig. 1, showing the construction and arrangement of details more plainly.

Fig. 3 is a transverse section through the device.

Fig. 4 is a fragmentary detail sectional view with parts in elevation showing the device inverted.

Fig. 5 is a perspective view of one of the vial holding brackets.

Referring to the drawing in detail, the reference character 1 designates the body portion of the level which is of usual rectangular form and which in the present instance is formed with a substantially ovate opening extending therethrough, and counterbored on its top and bottom. Fitted into the top or counter bore is a substantially ovate frame 2 and fitted into the bottom counter-bore is a frame 3 of substantially the same outline. The frame in each instance is provided with an overhanging lip 4 disposed in spaced relation to an inwardly extending flange 5, thus forming a channel between the lip and flange. The flange also forms a ledge upon which a transparent closure 6 rests, the closure being maintained in place by putty or other suitable retaining material 7.

It will be noted particularly from Figs.

2 and 3 that the flange of the upper frame 2 is provided with a depending rim 8 which is also ovate in general outline. This rim rests upon the flange 5 of the lower frame 3 as shown plainly in Fig. 3. At opposite ends, the rim is formed with spaced openings 9 through which the ends of a pair of liquid containing vials 10 extend. These vials are of usual form and contain the customary liquid and indicating bubbles.

In order to hold the vials in spaced relation, I provide, as before indicated, a pair of retaining brackets 11 of the form plainly shown in Fig. 5. Each bracket as here indicated comprises a split band 12 and an attaching tongue 13. The tongue is formed with an aperture and an appropriate screw or other fastening extends therethrough and into the flange 5 of the top frame 2.

It is obvious that with this arrangement the brackets can be adjusted with respect to each other to change the relationship of the two vials. It follows, also, that by being able to vary the relative relation in this manner, the two vials can be disposed in strict parallelism.

In installing the device in the body 1, an ovate hole is drilled through the same and it is counterbored on top and bottom for a depth to accommodate the thickness of the frames as indicated in Fig. 2. Around the margin or preferably at the opposite ends holes are drilled to accommodate internally screw threaded sleeves 14 and fastening screws 15 are passed through the frames and threaded into the sleeve. Also, if desired, packing rings 16 may be used to insure a good joint.

Referring to Fig. 4, it will be seen that the device is shown in an inverted position, the frame 3 at the top and the frame 2 at the bottom. Inasmuch as the frame 2 is placed in position first, it is desired to firmly fasten this in place. This is accomplished by using a washer 16' and fitting the same in an appropriately drilled recess and then passing the fastening screw 17 therethrough and into the sleeve here provided. This sleeve will be somewhat shorter than those before indicated.

It will be noted by this arrangement the frame 3 overlies the screw and renders it inaccessible and thus incapable of easy displacement. As stated, the top frame 2 is placed in position first in the ovate recess of the body 1 and previous to this the two

vials are mounted thereon and the brackets 11 are properly adjusted. This frame is thus firmly fastened in place and the other frame is put in position to complete the device.

It is believed that by considering the description in connection with the accompanying drawings, persons familiar with devices of this class will be able to obtain a clear understanding of the same. Therefore, a more lengthy description is thought unnecessary.

Minor changes coming within the field of invention claimed may be resorted to if desired.

Having thus described my invention, what I claim as new is:—

In a level of the class described, a body having an opening extending therethrough,

a pair of substantially similar frames disposed on opposite sides of said body, said frames being provided with channels, the bottoms of which constitute cover supporting ledges, covers fitted against said ledges, retaining means for said covers, a rim carried by one of said frames, said rim being provided at its ends with openings, a pair of liquid containing vials having their end portions extending through said openings, and retaining brackets extending through said openings and connected with said vials and with one of said frames, said retaining brackets being adjustably mounted, whereby to permit the relative positions of said vials to be regulated.

In testimony whereof I affix my signature.

JOSEPH AXT.
